UNITED STATES PATENT OFFICE.

SLOAN DANENHOWER, OF PELHAM MANOR, NEW YORK.

ATTACHMENT FOR SUBMARINE BOATS.

1,117,555.

Specification of Letters Patent. Patented Nov. 17, 1914.

Application filed March 5, 1914. Serial No. 822,563.

To all whom it may concern:

Be it known that I, SLOAN DANENHOWER, a citizen of the United States, residing at Pelham Manor, in the county of Westchester and State of New York, have invented certain new and useful Attachments for Submarine Boats, of which the following is a specification.

The object of the invention is to provide a simple and efficient method of and apparatus for salving submarine boats when submerged in extreme depths, that is in depths beyond practical and safe working distances of divers or the escape of the occupants of the boat through the escape hatches, the apparatus being permanently carried by the boats whereby, in the event of a boat being sunk and unable to rise through its own resources, the apparatus of another of such boats lying at the surface may be operatively connected to the apparatus of the submerged craft and the surface boat then utilized in raising the sunken craft sufficiently to permit the crew to escape through the escape hatches without the dangers incident to deep-sea diving or of towing the disabled boat into shallow water or into port where salvage operations may be practically carried out, means being provided for giving a distress signal which also serves to mark the location of the sunken boat and as a means for communicating with and supplying fresh air to the occupants until more powerful salving apparatus may be procured in the event of the surface submarine being unable to raise the sunken craft.

The invention consists in providing a submarine boat with hawsers which normally lie on the deck of the boat, said hawsers having one end extended respectively through a well formed in and extending vertically through the bow and stern of the boat and provided with shackles which lie against the bottom of the hull around the edges of the wells and having their opposite ends formed with loops to facilitate the attachment of the hawsers carried by a sister boat, the said loops having lifting lines permanently connected thereto which extend from a float detachably held in a pocket formed in the conning tower or deck of the boat so that when the float is detached it will rise and carry one end of the lines to the surface whereby the free ends of the hawsers may be drawn up thus avoiding the necessity of sending a diver down to the

boat when sunk in extreme depths, said float also having an air hose one end of which is extended into and made fast to the boat so that fresh air may be pumped into the sunken boat from the surface, and with telephone wires and connections for establishing communication with the sunken boat from the surface.

These and other features germane thereto constitute the invention as will be herein-after fully described and then claimed.

In the drawings, illustrating the invention, in the several figures of which like parts are similarly designated, Figure 1 is a diagrammatic side elevation of a submarine boat provided with my attachment, parts of the boat being shown in section to illustrate the location of the apparatus. Fig. 2 is a similar view in plan. Fig. 3 is a diagrammatic view illustrating a sunken boat with the float at the surface. Fig. 4 is a diagrammatic view illustrating the operation of salving one submarine with another such boat. Fig. 5 is a vertical longitudinal section drawn through one of the wells formed in the boat illustrating the clamping device for clamping the hawsers to the boat and the cutting devices for cutting the hawsers in case of emergency. Figs. 6 and 7 are horizontal sections drawn respectively on the lines *a—a* and *b—b* of Fig. 5. Fig. 8 is a plan view of one of the shackles carried by the hawsers.

1 designates a submarine torpedo boat of approved design having a superstructure 2, and conning-tower 3. In the bow and stern of the boat are located vertically disposed wells 4 which open through the skin and deck of the boat and in each well is held one end of a hawser or cable 5 which have their main lengths extended along the top or deck of the superstructure. To the ends of the hawsers extended into the wells are attached dogs 6 to which are detachably connected shackles 7 having flange base portions 8 of greater diameter than the lower ends of the wells and with ears or lugs 9 which extend into the wells and provided with wrist pins to which the dogs are connected. The bottoms of the base portions 8 are formed with perforated lugs 10 for engagement by hooks (not shown) carried by lines (not shown) for drawing the shackles onto the deck of the boat. The opposite ends of the hawsers or cables 5 are formed with loops 12 to facilitate the connection of the hawsers or cables

of another boat, as will be hereinafter described, and to the loops are connected one end of lifting lines 13 which extend from a float 14 detachably connected to the boat 5 and which is normally housed in a pocket 15 formed in the conning-tower or in the deck of the boat. To the float is connected one end of an air-hose 16 having its opposite end extended into and made fast with the boat 10 and through which fresh air may be pumped into the boat to succor the crew while the salvage operations are being carried out. The float also carries telephone wires (not shown) for establishing communication between the boat and the surface. In practice 15 the lifting lines and air-hose will be wound in the bottom of the housing as shown in Fig. 1, and the telephone wires will be arranged in the hose. Each well 4 is constructed in sections which are connected together and to the skin of the boat air- and water-tight and are constructed to withstand a pressure equal to that for which the main hull is designed. The top flanges of the 20 upper sections of the wells are connected to the under side of the hull plating while the lower flanges of the bottom sections are connected to the outside of the hull and to facilitate the fitting of the said lower sections to the boat I taper them sufficiently so that the peripheries of the top flanges will be of practically the same diameter as the lower ends of the tubular body section of the members. This construction permits of 25 the insertion of the upper flanges through the holes in the hull and at the same time permits the peripheries of the said lower members to lie snugly against the edges of the openings and thus provide a thoroughly 30 rigid connection.

In the upper ends of the wells are arranged clamps for fastening the hawsers to the boat and which comprise fixed sections 17 and movable co-acting sections 18 35 the latter being carried at the outer ends of threaded shafts 19 which operate in threaded bores formed in stuffing boxes 20 formed upon or integral with and upon the outside of the wells, the inner ends of the shafts being provided with hand wheels 21 by which the shafts are rotated to adjust the movable members of the clamps toward or away from the fixed members thereof. The movable members are provided with short pins 40 45 50 55 60 65 22 which work in sockets formed in the stuffing-boxes to prevent the movable members from turning on their shafts and the outer faces of the fixed and movable members are formed with vertical grooves which are filled with Babbitt metal so that when the movable members are adjusted to clamp the cables or hawsers between them and their co-acting fixed members the metal will be forced into the grooves between the 65 strands of the cables and thus positively

prevented from slipping when strain is placed upon the cables.

In the lower ends of each well is arranged a cutting device for cutting the cables or hawsers in case of emergency and 70 these cutters comprise a fixed member 23 having cutting edges 24, and movable members 25 carried by threaded shafts 26 which operate in stuffing boxes 27 formed integral with or connected to the outside of the lower 75 sections of the wells, handles or hand-wheels 28 being connected to the inner ends of the shafts by which they are rotated to adjust the movable members into and away from the fixed members, and the said movable 80 members are also provided with guide pins 29 to prevent them from turning similar to the pins carried by the movable members of the clamps.

Where my invention is installed upon 85 boats having superstructures that extend practically throughout the full length of the main hulls I arrange pipes 30 in the space formed by the superstructure which provide extensions of the wells as shown in Fig. 90 3, and it will be understood that the after wells are extended through the keels of the boats for obvious reasons.

The method of operating my invention is as follows: We will assume that a boat is 95 disabled while cruising with a fleet of submarines and is lying on the bottom in say 125 feet of water. On the first sign of accident the float is released which immediately rises to the surface which not only 100 enables those on the boats at the surface to quickly locate the sunken craft but also to establish communication with the same and if necessary to pump quantities of fresh air into it. When the float is picked up by the 105 boat on the surface the hawsers of the latter are withdrawn from the wells by first lowering the shackles so that a line may be made fast thereto to draw them onto the deck of the boat where the shackles are detached 110 from the cables so that they may be withdrawn from the wells. The cables or hawsers of the sunken craft are then drawn to the surface by their lifting lines and passed upwardly through the wells of the surface 115 boat and attached to suitable floats or buoys 30' and the latter then positioned over the tops of the wells, the hatches of the boat at the surface are then closed and locked after 120 which water ballast is admitted to the ballast tanks to submerge the boat, to say ten feet, and as the boat sinks and the water surrounds the buoys 30' they will be floated to thus hold the cables or hawsers elevated 125 so that the rescuing boat will slide down them so to speak. Now when the desired depth has been reached the clamps are made fast to the cables, the ballast tanks then blown to restore the buoyancy of the rescuing boat to thus determine if the latter 130

- possesses sufficient buoyancy to overcome the dead weight of the sunken boat and to lift it from the water-bed. Should this condition prevail water-ballast is again admitted 5 to the tanks to submerge the boat to a greater depth to obtain a grip on the cables or hawsers nearer the sunken boat. When this operation is completed the tanks are again blown to restore the buoyancy of the 10 rescuing boat which will rise to the surface and then proceed under its own power into port or into shallow water with the disabled craft suspended under it and where the crew of the boat may escape and the work of 15 salvage more conveniently carried out. This operation is exceedingly simple and while described in connection with a rescuing submarine it will be evident that any surface vessel provided with sufficiently powerful 20 hoisting apparatus could as effectively raise the sunken submarine boat provided the latter carried my improved attachment, and in this connection it might be stated, that the floats or buoys will be provided with such 25 data to state the cause of their presence on the surface, so that, if discovered by any surface vessel communication may be established with the sunken boat to ascertain if life exists on board, the necessity of urgent 30 assistance, and so forth, before communication is established with the nearest authorities for the despatch of an available rescuing submarine or other salvage boat. However, when a boat sinks to much greater 35 depths, say to 250 feet, the salvaging operations as above described would be impracticable since the inherent difficulties attendant upon working at such depths render the operation extremely slow and fraught 40 with many dangers both to those imprisoned in the sunken boat and to the divers. With the use of my invention, however, when a boat sinks to such depths the hawsers are drawn up as previously described and their 45 hauling lines made fast to the cleats on the deck of the rescuing submarine, the shackles of the hawsers of the said boat are then detached and the hawsers then lowered to the tops of the hawsers of the sunken boat this 50 being readily done by slipping the lifting lines through the loops of the hawsers so that they will slide on the lines, a diver then is sent down either from the rescuing submarine boat or from a surface vessel to 55 make the dogs of the lowered hawsers fast with the hawsers of the sunken boat, then as previously described floats are attached to the upper ends of the hawsers and the submarine submerged, a grip taken on the 60 hawsers, and the tanks then blown to restore the buoyancy of the rescuing boat to thus lift the sunken boat so that it may be towed into shallower water where the operation is repeated until the boat is moved into waters 65 shallow enough to permit the crew of the disabled boat to escape without unnecessary danger and where the salvage operations may be carried out to better advantage. It will thus be seen that my apparatus and my method of salvaging submarine boats is extremely simple, and requires but a comparatively short time to carry out the operation, and one which may be readily installed upon boats at little cost. 70
- Submarine boats equipped with my apparatus will be independent of salvage vessels since they are capable of rendering aid to one another which is of inestimable advantage especially when operating at sea distant from port, and even though a boat 80 may be sunk in waters below diving depths the hawsers of the sunken vessel may be drawn near enough to the surface to permit a diver to work so that the hawsers of the succoring boat may be attached to those 85 of the sunken boat to raise and convey the latter into shallow water as previously described. Furthermore during the salvage operation the air line of the sunken boat may be connected to the air-line of the surface 90 boat so that fresh air may be supplied to the disabled craft and the lives on board the latter thus sustained until the boat is moved into waters shallow enough to permit the crew to escape. It may also be stated that 95 even should the rescuing boat not have sufficient reserve buoyancy to lift the disabled boat to the surface it may, at least, reduce the dead weight sufficiently to permit of the boat being dragged over the bottom into 100 shallow water.
- What I claim is:—
1. A hoisting attachment for raising sunken submarine boats, comprising in combination with a submarine boat having a well in the bow and stern thereof, hawsers carried on the deck of the boat, each hawser having one end extended into one of the wells and provided with a dog and its opposite end provided with a loop, and a shackle connected to each dog and engaging the hull of the boat. 105
  2. A hoisting attachment for raising sunken submarine boats, comprising in combination with a submarine boat having a well in the bow and stern thereof, hawsers carried on the deck of the boat, each hawser having one end extended into one of the wells and provided with a dog and its opposite end provided with a loop, a shackle 110 connected to each dog and engaging the hull of the boat, and a clamp arranged in each well operable from within the boat. 115
  3. A hoisting attachment for raising sunken submarine boats, comprising in combination with a submarine boat having a well in the bow and stern thereof, hawsers carried on the deck of the boat, each hawser having one end extended into one of said wells and provided with a dog and its op- 120
  - 125
  - 130

- posite end provided with a loop, a shackle connected to each dog and engaging the hull of the boat, and a float having a lifting line connected to each of said loops, said 8 float being detachably connected to said boat, as and for the purpose specified.
4. A hoisting attachment for raising sunken submarine boats, comprising in combination with a submarine boat having a 10 well in the bow and stern thereof extending vertically through the hull, hawsers carried on the deck of the boat, each hawser having one end extended into one of said wells and provided with dogs and having its opposite end provided with a loop, a shackle detachably connected to each dog and engaging the hull, a hawser clamping device arranged in each well and operable from within the boat, a hawser cutting device 15 also arranged in each well and operable from within the boat, a float detachably connected to the boat, and lifting lines carried by the float and connected to the loops of said hawsers.
5. An improved attachment for submarine boats for raising and succoring a sunken submarine boat by and from a submarine boat floating at the surface, comprising in combination with submarines having wells 20 extending through the hulls thereof, hawsers or cables carried on the decks of the boats, each hawser having one end extended into one of the wells of its boat and provided with shackles which engage the 25 bottom of the hull, floats detachably connected to the boats and having lifting lines connected to said hawsers, for the purpose
- specified, and means for securing the hawsers of a sunken boat to a submarine boat floating at the surface, for the purpose 40 specified.
6. An improved attachment for submarine boats for raising and succoring a sunken submarine boat from a sister boat floating at the surface, comprising in combination with 45 submarines having wells extended through the hulls thereof, hawsers carried on the decks of the boat each hawser having one end extended into one well of its boat and having shackles detachably connected to 50 said ends and loops formed on the opposite ends, a float detachably connected to each boat, lifting lines carried by said floats and connected to the hawsers of their boats, air-supply hose carried by the floats, and 55 hawser clamping devices arranged in said wells for locking the hawsers from a sunken boat to a surface boat, said clamping devices being operable from within the boats, substantially as and for the purposes 60 specified.
7. In a submarine torpedo boat, a well formed in the bow and stern thereof adapted for holding a hawser or lifting cable, a hawser clamping device arranged in each 65 well and operable from within the boat, and a hawser cutting device also arranged in each well and operable from within the boat.

In testimony whereof I have hereunto set my hand this 4th day of March, A. D. 1914. 70

SLOAN DANENHOWER.
